DESIGN FOR A LINK UNIT FOR FRUIT GRADING APRONS OR THE LIKE

Foster B. Fuller, Perinton, and Arthur R. Adams and Clarence P. Le Frois, Fairport, N. Y., assignors to The Trescott Company, Inc., Fairport, N. Y., a corporation of New York

Application May 13, 1938, Serial No. 77,172

Term of patent 14 years

To all whom it may concern:

Be it known that we, Foster B. Fuller, Arthur R. Adams, and Clarence P. Le Frois, all citizens of the United States, residing at Perinton, Fairport, and Fairport, respectively, in the county of Monroe and State of New York, have invented a new, original, and ornamental Design for a Link Unit for Fruit Grading Aprons or the Like, of which the following is a specification, reference being had to the accompanying drawing, forming part thereof.

In the drawing:

Fig. 1 is a top plan view of a link unit for fruit grading aprons showing our new design;

Fig. 2 is an edge view thereof, and

Fig. 3 is a bottom plan view thereof.

We claim:

The ornamental design for a link unit for fruit grading aprons or the like, as shown.

FOSTER B. FULLER.

ARTHUR R. ADAMS.

CLARENCE P. LE FROIS.
